UNITED STATES PATENT OFFICE.

LOUIS W. DOWNES, OF PROVIDENCE, RHODE ISLAND.

ELECTRIC FUSE.

No. 846,404.

Specification of Letters Patent.

Patented March 5, 1907.

Application filed December 8, 1903. Serial No. 184,308.

To all whom it may concern:

Be it known that I, LOUIS W. DOWNES, a resident of Providence, Rhode Island, have invented a new and useful Improvement in Electric Fuses, which invention is fully set forth in the following specification.

This invention relates to inclosed fuses, particularly to those having projecting terminals adapted to engage circuit-terminal clips.

More specifically, my invention comprises means for forming a strong, durable, and rigid joint or connection between the terminal and the cap through and from which it projects.

The improvements constituting the invention will be most readily understood by reference to the accompanying drawing, wherein—

Figure 1 is an elevation, partly in section; and Fig. 2, an end view of one embodiment of the invention.

Referring to Figs. 1 and 2, 1 is a tubular shell, of fibrous or other non-conducting material, closed at its ends by metallic caps 2, which thus constitute parts of the complete inclosing casing. Each cap is secured to the tubular part in any suitable manner and has

vent-holes 4 and an elongated opening 5. 6 is a fuse-link, which may be of any suitable form, that shown being tubular and having flattened blade-like link-terminals, which project through the elongated slots or openings 5 in the caps and constitute projecting

35 fuse-terminals 6 on the casing.

12 is the usual filling of non-conducting material.

In order to provide a strong and rigid joint between the fuse-cap and the terminal, I provide a flange 7 on the cap about opening 5. The somewhat extensive inner surface of the flange closely fits the terminal and affords a large area of surface for soldering the parts together. As shown in Figs. 1 and 2, the flange is struck up from a plate 8, which latter is sweated or soldered to the cap about opening 5. As here shown, the flange projects outward. It may, however, project inward, as shown in my Patent No. 773,201, dated October 25, 1904.

50 What is claimed is—

In an inclosed electric fuse, a fuse-link, a shell, a cap closing an open end thereof and having an opening therethrough, a plate secured to the cap and having an opening therethrough in alignment with the opening in the cap and a flange on said plate around the opening therein, a terminal electrically connected with the fuse-link and projecting through openings in and beyond the cap and 60 flanged plate to constitute a fuse-terminal, said flange fitting closely about said terminal and rigidly connecting it with the cap.

In testimony whereof I have signed this specification in the presence of two subscribing witnesses.

LOUIS W. DOWNES.
